UNITED STATES PATENT OFFICE.

SOREN S. ADAMS, OF ASBURY PARK, NEW JERSEY.

FOLDING ORNAMENT.

Application filed June 4, 1925. Serial No. 34,872.

This invention relates, generally, to improvements in ornaments, and, the present invention has reference, more particularly, to that class of folding ornaments, such as are made of paper, and which are ornamental in effect, being used more especially for holiday decorations, usually in the form of colored paper spheres, bells, and the like.

Ornaments of the character above stated

- 10 usually comprise a pair of hingedly connected discs or members, usually of a semi-circular or other desired marginal configuration, to which is suitably attached the paper-ornament, arranged in a manner, so that
- 15 when the discs are brought side by side, the paper-ornament is opened out in a manner to produce a complete sphere, or other ornamental figure, and that when the hinged discs are brought into a closed relation, the
- 20 paper-ornament is also closed up and is embraced by the two hinged discs.

The present invention has for its principal object to provide a novel folding ornament of the decorative type hereinafter

- 25 more fully set forth, and in which the hinged portions of the ornament, carrying discs or members are spring-actuated, so that the hinged discs are automatically brought into their opened out relation, and in close contact with each other, so that the paper-ornament in that instance will produce a perfect figure, such as a sphere, bell, or the like.
- 30

Other objects of the present invention not at this time more particularly enumerated will be more fully understood from the following detailed description of the present invention.

With the various objects of the present invention in view, the said invention consists, primarily, in the novel decorative ornament hereinafter set forth; and, the said invention consists, furthermore, in the novel arrangements of the several parts of the ornament, as well as in the details of the construction of the said parts, all of which will be more fully described in the following specification, and then finally embodied in the clauses of the claims which are appended to and which form an essential part of the

50 said specification.

The invention is illustrated in the accompanying drawings, in which:

Figure 1 is an elevation of a decorative ornament in sphere-form, showing one embodiment of the principles of the present invention; Figure 2 is a similar view of

the same, showing the paper-ornament provided discs in an opened-out relation, and said view illustrating more particularly one construction of spring-controlled hinge-connection between the said discs; and Figure 3 is a view of the ornament, showing one of the hinged discs of the ornament in elevation, and the other disc being shown in end or edge-view.

Figures 4, 5 and 6 are views similar to Figure 2, showing the discs of the ornament provided with modified forms of hinge-connections.

Figure 7 is another view, similar to said Figure 2, showing the discs of the ornament provided with another modified form of hinge-connection; Figure 8 is a view, showing fragmentary portions of the disc, when looking at the reverse sides of the discs represented in said Figure 7; and Figure 9 is a sectional representation, taken on line 9—9 in said Figure 7, the hinged discs being shown in a position at right angles to each other.

Figure 10 is another view, similar to said Figure 2, showing still another modified construction of spring-controlled hinge-connection.

Similar characters of reference are employed in the said above described views, to indicate corresponding parts.

Referring now more particularly to Figures 1, 2 and 3 of the drawings, the reference-character 1 indicates a complete decorative ornament made according to and embodying the principles of the present invention, the device here shown being of a spherical configuration, when the several parts are arranged in the manner indicated in Figure 95

1. As shown, the device consists of a pair of semi-circular, or other suitably shaped discs or members, as 2 and 3, which are suitably connected along their marginal edge-portions 4 and 5, so as to be adapted to be folded upon each other, by means of suitable hinge-members 6 and 7. In practice, these discs 2 and 3 are usually made from card-board, and the hinge-members 6 and 7 may be made of paper, linen, or other suitable fabric, suitably secured to the said discs by means of glue, mucilage, or paste, as will be evident. Instead of making the discs 2 and 3 of card-board, the discs may be made of thin metal, such as tin, in which case the hinge-members may also be made of metal. Suitably attached to and covering

the opposite or outer face-portions of the said discs is the ornamental or decorative element or member 8 of the device, the same being made of colored paper and being collapsible or foldable in the manner usual in devices of this kind, the general configuration of the member 8 being of a cellular, honey-comb, or accordion-like effect, as will be evident from an inspection of said Figure 1.

In connection with the hinged portions of the discs 2 and 3 is employed a torsion-means, the purpose of which is to automatically force the hinged discs from an opened-out relation, as shown in Figures 2 and 3 of the drawings, into their closed relation, adjacent to each other, whereby the decorative element 8 assumes a position, such as is illustrated in Figure 1.

The torsion-means used with the device represented in said Figures 1, 2 and 3 consists of a wire 9 provided intermediate its ends with a suitable number of coils 10, which provide a spring, arranged in suitably cut away portions 11 and 12 of the respective discs, as shown. The end-portions of the wire are disposed beneath the respective hinge-members 6 and 7, and are suitably bent, as at 13 and 14, to provide hook ends which are passed through the respective discs 2 and 3, to the opposite sides thereof, for securing the said torsion-means in its operative relation to the said discs, as will be evident.

The arrangement of the spring across the joint between the hinged discs 2 and 3 is such, that when the discs are in an opened-out relation, a strain is brought upon the coils 10, which tends to close the said discs 2 and 3 upon each other, to provide a folding ornament, such as is illustrated in Figure 1 of the drawings.

In lieu of the spring-controlled hinge-construction herein-above described, a torsion-means, such as is shown in Figure 4 of the drawings, may be employed.

In the device there shown, the arrangement and construction of the discs 2 and 3, the hinge-members 6 and 7, and the ornamental or decorative element 8 is the same as that heretofore described in connection with the device illustrated in said Figures 1, 2 and 3. The torsion-means, however, consists of a wire 15 provided intermediate its ends with a series of coils 16. The end-portions of the wire 15 are suitably bent to provide hooks, as 17 and 18, which are arranged beneath and suitably secured to the respective discs 2 and 3, by means of suitable fasteners or staples 19 and 20, as will be understood from an inspection of said Figure 4.

In the modified construction, shown in Figure 5 of the drawings, a straight spring-wire 21 is employed, the intermediately disposed coils in this construction being dis-

pensed with. The end-portions of this wire 21 may also be suitably bent to provide hooks, as 22 and 23, which are arranged beneath and suitably secured to the respective discs 2 and 3, by means of suitable fasteners 70 or staples 24 and 25, as shown.

Referring now to the construction represented in Figure 6 of the drawings, two discs 26 and 27 are employed, these discs being made from sheet metal. Near one end 75 of the marginal edge 28, the disc 26 is provided with a hinge-ear 29, and at its other end, a cut-away portion or recess 30 is provided. In a similar manner, the disc 27 is provided at its marginal edge 31 with a hinge-ear 32 adapted to register with the cut-away portion or recess 30, said edge 31 being also provided with a cut-away portion or recess 33, into which the hinge-ear 29 is adapted to be fitted. A spring torsion wire 85 34 is inserted through the said ears 29 and 32, the main portion of said wire located between the said ears extending directly across the joint formed by the marginal edges 28 and 31 of the respective hinged 90 discs, as shown, and the said wire being provided at its end-portions with angularly extending retaining members, as 35 and 36, held against the faces of the respective discs 26 and 27, by suitable retaining means, as 37 95 and 38. The operation of this form of ornament shown in said Figure 6 will be fully understood from an inspection of said view.

Referring now to the construction represented in Figures 7, 8 and 9 of the drawings, two discs 39 and 40 are employed, the disc 39 being formed with a pair of suitably located holes or perforations 41 and 42, and a connecting slotted portion 43 formed by an angularly bent part of the said disc 39, in the form of a flange or lip, as 44. The other disc 40 is also formed with correspondingly located holes or perforations 45 and 46. The hinge-connection for the two discs 39 and 40 in this case, is an elastic band 47, the end-portions 48 and 49 of which are inserted in the holes or perforations 45 and 46 being secured in place by suitable retaining discs 50, or other fastening means, and the main body-portion of the said band 47 being sprung behind the said lip or flange 44, substantially as shown.

In Figure 10, I have illustrated still another modified hinge-connection for the collapsible discs 51 and 52 of the ornament. In this construction, the disc 51 is provided with a pair of perforations 53 and 54, and the disc 52 is provided with correspondingly located perforations 55 and 56. A cord or tape 57 is threaded through these perforations, as shown in said Figure 10, the respective ends 58 and 59 of the said cord or tape 57 being suitably fastened to the hook-shaped end-members 61 and 62 of a suitably formed spring 60, made from a piece of resilient

wire, which is suitably maintained in its operative relation upon the face of the disc 52 by a loop-shaped staple or eye 63, as shown. The operations of the forms of ornaments illustrated in said Figures 7, 8, 9 and 10 of the drawings, will be fully understood from an inspection of the several views illustrative of these two modifications of the folding ornament.

10 Of course I am fully aware that the present invention is capable of many other modifications, without departing from the scope of the principles of the present invention, as set forth in the foregoing specification.

15 Hence, I do not limit my present invention to the exact arrangements and combinations of the several devices and parts as described in the said specification, nor do I confine myself to the exact details of the construction 20 of the said parts, as illustrated in the accompanying drawings.

I claim:

1. A folding ornament, comprising a pair 25 of body members, having straight inner edge portions disposed in adjoining edge to edge alignment, an expansible element interconnected between opposed faces of said body members, hinge means pivotally connecting said body members together at their adjoining straight edges, spring means cooperating with the adjoining marginal portions of said body members, said spring means by its tension operating to turn said body members on said hinge means to expand 35 said expansible element, and said spring means being entirely concealed when said body members are so turned thereby.

2. A folding ornament, comprising a pair 40 of body members having straight inner edge portions disposed in adjoining edge to edge alignment, an expansible element intercon-

nected between opposed faces of said body members, hinge means pivotally connecting said body members together at their adjoining straight edges, a torsion spring in substantial alignment with said adjoining straight edges of said body members, anchoring means at the opposite ends of said spring respectively secured to the respective body members, said torsion spring 50 by its tension operating to turn said body members on said hinge means to expand said expansible element, and said torsion spring being entirely concealed when said body members are so turned thereby. 55

3. A folding ornament, comprising a pair of body members having straight inner edge portions disposed in adjoining edge to edge alignment, an expansible element interconnected between opposed faces of said body members, hinge means pivotally connecting said body members together at their adjoining straight edges, a torsion spring in substantial alignment with said adjoining straight edges of said body members, angular extensions projecting respectively from the respective ends of said spring, said extensions respectively overlying opposed faces of the respective body members, fastening means for securing said extensions 65 against displacement from said body members, said torsion spring by its tension operating to turn said body members on said hinge means to expand said expansible element, and said torsion spring being entirely 70 concealed when said body members are so turned thereby. 75

In testimony, that I claim the invention set forth above I have hereunto set my hand this 29 day of May, 1925.

SOREN S. ADAMS.
